EXTENSIBLE BRACELET

William Kastner, Irvington, N. J., assignor to
Forstner Chain Corporation, a corporation of
New Jersey

Application June 14, 1939, Serial No. 279,027

1 Claim. (Cl. 24—71)

My present invention relates to the bracelet art, and has particular reference to a novel construction for extension bracelets, whereby the length of the bracelet in closed position may be changed as desired, and whereby a comparatively large extension is provided in open position for comfortably removing from the wrist.

It is the principal object of my invention to provide a bracelet construction which permits extension of the bracelet beyond the normal length of the bands, when opened for removal from the wrist.

Another object of my invention is to provide a bracelet which permits instant detachment and separation of easily manipulated parts, so as to facilitate removal and mounting of the bracelet.

A further object of my invention is to provide a construction which will insulate the metals in the band against tarnishing caused by electrolysis.

A further object of my invention is to provide a construction having a detachable connection, the parts being so arranged that the ends of the bracelet are never completely separated, whereby the wrist watch cannot fall to the ground.

A further object of my invention is to provide an extension bracelet construction which includes a small number of readily manufactured parts, and which is positive in action, whereby the length of the bracelet may be adjusted to fit the wrist of the wearer.

With the above and other objects and advantageous features in view, my invention consists of a novel arrangement of parts more fully disclosed in the detailed description following, in conjunction with the accompanying drawing, and more specifically defined in the claim appended thereto.

In the drawing:

Fig. 1 is a plan view of the novel bracelet construction;

Fig. 2 is an edge view thereof;

Fig. 3 is a similar view, the clasp being open;

Fig. 4 is an enlarged perspective view of the extension plate;

Figs. 5 and 6 are enlarged perspective views of the parts of the extension plate;

Fig. 7 is an enlarged perspective view showing the bracelet length adjusting parts; and

Fig. 8 is an enlarged perspective bottom plan view of the attachment device for releasable attachment to the lock arrangement of Fig. 7.

The present invention relates to extension bracelets of the type in which two bands are mounted in overlapping relation, a lock device

5 being adjustably positioned on the lower band, and an attachment arrangement being mounted on the upper band. The essential feature of the present arrangement resides in the provision of an extension plate on the lower band which provides a swinging extension when the limit of the sliding extension has been reached.

Referring to the drawing, the bracelet 10 includes a lower strap portion 11, see Figs. 2 and 3, which has an end hook 12 for attachment to the bail at one side of a wrist watch, and an extension plate 13 and slide link 14 through which an upper strap portion 15 may be longitudinally moved; this upper strap portion 15 also having an end hook 16 for attachment to the other bail of the wrist watch. The lock device 17 is adjustably slidably positioned on the strap portion 11, and may be locked in place along the length thereof so as to change the effective length of the bracelet, the strap portion 15 having an attaching element 18 which is detachably securable to the lock device 17.

The extension plate 13 is preferably made with a steel surface on one side and a gold surface 25 on the other side for a purpose hereinafter to be described. This can be done by plating or the like; however, to avoid the expense and difficulty of plating or otherwise coating one side only, I have devised the construction illustrated in Figs. 4, 5 and 6. In the illustrated construction, the plate 13 comprises a lower plate portion 19, preferably of gold, curved to fit the wrist, and having integral side flanges 20. The portion 19 is also provided at one end with the spaced ears 21, and at the opposite end with a reentrantly bent portion 22 having integral, laterally extending portions forming pivot pins 23. The side link 14 is pivotally mounted on the pivot pin 23.

The upper plate portion 24, preferably stamped 40 from sheet steel, and curved to fit between the flanges 20, is provided at one end with an ear 25 adapted to fit between the ears 21, the opposite end being pinched under the reentrantly bent portion 22 of the lower portion 19. The 45 ears 21 and 25 are mounted on a pivot pin 26 of a conventional end connector clamped to the strap portion 11.

The adjustment device and detachable connection may be of any well-known type; however, for purposes of illustration only, I have shown the construction described in detail in my copending application Serial No. 252,174, entitled Watch attachment. In the illustrated construction, see Figs. 5 and 6, the lock device 17 comprises a base 27 having a bottom plate 28

and two side plates 29, each side plate having a longitudinal slot 30 for receiving the end lug 31 of a connector element 32. The connector element 32 has a flat plate portion 33 adapted to engage the top of the strap portion 11, which strap portion extends through and overlies the base plate 28; the connector element 32 extends upwardly and then horizontally and then downwardly to form a hook receiving chamber which has a slot 34 for receiving connector hooks as hereinafter explained.

A cam element 35 is rotatably mounted on a pivot 36 which has its ends secured in the plates 29, the cam having an outwardly extending finger portion 35a, which when manually pressed down rotates the cam end 38 firmly against the plate 33 so as to thrust the plate downwardly into locking engagement with the strap portion 11. The slots 30 are made large enough to permit the necessary up and down movement of the lugs 31.

The attachment device 18 includes a base 39 having sides 40 each of which has slots 41 of relatively large width, and narrower slots 42 adjacent thereto. The sides 40 have openings 43 for receiving the pivot ends 44 of an end connection 45 which is locked to the end of the strap portion 15. Positioned on the base of the connector 39 are two hook elements 46 having ends 47 which project outwardly through the slots 41. The two hook elements 46 are resiliently urged away from each other by an expansion spring (not shown) housed on the base 39 between them and covered by a cover plate 48 which has a recess 49 to accommodate the spring, and which has end lugs 50 which extend through and are received in the slots 42.

With the parts assembled as shown in Figs. 7 and 8, the ends 47 of the hook elements may be manually pressed inwardly against the action of the spring to move the hook portions towards each other. They may then be inserted into the slot 34, and the spring will push the hook elements apart and cause them to engage the connector element 32. Preferably, the ends of the hooks may be rounded so that the inward movement is automatically accomplished by pressing down on the connector element. To adjust the bracelet length, the finger lever 37 is raised, thus releasing the plate 33 from locking contact with the strap portion, whereupon the entire lock device may be moved lengthwise of the strap and locked to a new position.

When the attachment device 18 is locked to

the lock device 17, the extension plate 13 is folded over the lower strap 11 so that it acts as a separator between the straps 11 and 15, the upper strap 15 nesting between the flanges 19, as in Fig. 2. In removing the strap from the wrist, the attachment device 18 is unhooked from the adjustment lock 17 and the upper strap 15 slides in the usual manner until the slide link 14 stops further movement. At this point, unfolding of the extension plate 13 to the position shown in Fig. 3 will afford an additional extension.

The use of the described extension plate 13, having opposite gold and steel surfaces, as a separator between the overlapping portions of the straps 11 and 15, is highly advantageous when utilizing the type of strap illustrated, wherein a flexible steel mesh 50 is provided with an upper outer covering of gold strips 51. The salty body perspiration seeping between the overlapping straps causes an electrolysis between the different metals which tarnishes the straps. However, by constructing the extension plate 13 from the same metal as the mesh 50 on one side, and the same metal as the strips 51 on the other side, there can be no electrolysis or tarnishing; gold being placed against gold, and steel against steel.

All of the parts are preferably made of stamped sheet stock, this construction lending itself to rapid and inexpensive manufacture and to rapid assembly, whereby the cost of manufacturing is greatly reduced. The parts may be ornamented as desired, either by engraving, plating, enameling, or the like.

While I have described a specific constructional embodiment of my invention, it is obvious that the size and shape of the parts, the material used for the parts, and their relative positioning and operation, may be changed to suit the requirements for different bracelet designs, without departing from the spirit and the scope of the invention as defined in the appended claim.

I claim:

In a bracelet construction, two strap portions in overlying relation, one of said strap portions having a lock device and the second strap portion having an attachment device detachably secured to said lock device, a slide connection through which the first strap portion is freely slidable, and a curved extension plate having one end hingedly secured to the second strap portion and the other end hingedly secured to said slide connection.

WILLIAM KASTNER.
